CLAIM

The ornamental design for an ophthalmic applicator for
irradiation of intra-ocular tumors or the like, as shown
and described.

DESCRIPTION

FIG. 1 is a bottom plan view of an ophthalmic applicator
for irradiation of intra-ocular tumors or the like,
showing our new design;

FIG. 2 is a side elevational view thereof, the opposite
side being identical thereto;

FIG. 3 is a top plan view thereof; and

FIG. 4 is a perspective view thereof.

FIG. 1

FIG. 2

FIG. 3

FIG. 4
